UNITED STATES PATENT OFFICE

GEORGES BARIQUAND, OF PARIS, FRANCE

CARBURETOR

Application filed January 23, 1930, Serial No. 422,925, and in France February 21, 1929.

Multiple jet carburetors are known in which a general central suction passage is fed by two radiating suction channels each provided with a jet, and whose entry into service is automatically regulated by a distributing slide valve or member with adjustable openings, sliding in the bore of the body itself of the carburetor, the length and relative disposition of the openings in the 10 slide member which are preferably staggered, being adjusted in such a manner that each channel comes into operation at the moment when the depression produced by the suction of the motor causes this slide member 15 to take up a corresponding position, the slide member which is free, rising up to a point of equilibrium between its weight and the depression produced above it, the rise and fall movements being braked by an entry 20 (or exit) of air which is regulatable and provided at the end of the body of the carburetor and consists of an adjustable graduated or calibrated aperture which is called the "compensating hole".

25 This automatic displacement of the distributing slide member can be effected by different inherent causes either due to its manner of guiding or to its pneumatic function and to the forces which intervene to 30 provoke its displacement to suit the different speeds of the motor.

It happens in fact, that, on the one hand, the deformation of the flange of the body of the carburetor (when tightened onto the 35 inlet pipe) causes the ovalizing of the bore of the body, and it is important, in order to avoid the jamming of the slide member, to render the lining in which the slide member moves, independent of the body itself 40 so as to free it of all function other than for guiding the said slide member.

On the other hand, the leakages which occur along the generatrices of the slide member are detrimental to the constant balance 45 or equilibrium of the slide member to the different speeds (equilibrium between the weight of the slide member and the depression which exists), and are hence objectionable.

50 To cease to be tributary to the inevitable

wear of the parts and to permit of matching the slide member with a certain tolerance sufficient to avoid jamming, the constancy of these leakages in time is ensured by providing peripherally of the slide member 55 and towards its lower part, one or more grooves into which a longitudinal groove or channel finds its outlet, and kept in constant communication with the exterior.

This communication is effected by a hole 60 pierced in the body of the carburetor, the same groove or channel serving moreover for the guiding of the slide member, by the engagement of a key or screw integral with the body of the carburetor. The leakages are 65 then collected, run into channels and adjusted in delivery or output by the circular groove or grooves and the longitudinal channel.

70 It will be seen, moreover, that the slide member loses its continuous oscillatory movement at the different speeds, becomes stabilized and the general operation of the carburetor is improved.

Nevertheless to prevent condensation of 75 the petrol at the center of the slide member, the internal capacity of the same is partitioned in such manner as to guide and direct separately the different fluid veins, so that the mixture of these fluid veins is effected above the slide only, in the body itself 80 of the carburetor.

85 The accompanying drawings show, by way of example, several forms of construction of the carburetor with its slide member and in particular:

Fig. 1 is a longitudinal section taken on the line 1-1 of Fig. 2;

Fig. 2 a horizontal section taken on the line 2-2 of Fig. 1;

Fig. 3 a partial vertical section taken on the line 3-3 of Fig. 2 showing the longitudinal channel;

Fig. 4 a front view of the slide member. 95

The upper body 1 carries the throttle valve 2, the flange 3 of the carburetor, the slow running means 4 and the heating means 5. This part has a sufficiently rigid shape to completely absorb the deformations of the flange 3 at 100

the moment when it is tightened up to the inlet pipe.

The lower part 6 of this body is machined to make a joint with a collar 7 carried by the independent central lining 8 and these two faces are brought firmly one against the other by tightening with pins, screws or by a peripheral screw thread.

The lining 8 is engaged freely in the interior of the bore 9 of the body 1 and for this reason is completely isolated free and without any flange. The deformations of the flange give rise to no risk in being forced closer and closer, of ovalizing the lining 8 and jam the drawer 10 which moves in its interior.

Another advantage of this arrangement is to permit an easy dismantling of the central part when making adjustments, without having to completely dismantle the carburetor secured on the motor, the central lining 8, which is the regulating means (by reason of the characteristics of its air inlet channels 11a, 11b, 11c, 11d) is therefore accessible and interchangeable without having to change the carburetor itself.

The distributing slide member consists of a sleeve 10 completely closed at its lower part by a plug 12.

The slide is housed in a freely adjustable manner in the bore 8 and has in its outer side a vertical guide channel 13 which is engaged by a screw 14 which is threaded in a radial opening in the member 7. Between the built up or inserted end 15 of the lining of the carburetor and the lower plug 12 of the slide member there is only left a small space 16 which communicates with the atmosphere through an adjusting aperture 17 called the compensating hole, pierced in an exchangeable screw.

By reason of the depression force produced by the suction of the motor above it, the slide member tends to rise. It rises in fact but in a regular movement by the inlet of air forced by the atmospheric pressure through the aperture 17.

By suitably proportioning the weight of the slide member 10 and the dimension of the hole in the depression screw 17, the result is obtained that this slide member automatically takes up all the positions which are necessary for the perfect running of the motor from its starting-up until, its maximum speed, by unmasking successively, by means of the ports 18a, 18b . . . , the different suction channels 11a, 11b, . . . radiating in appropriate number, the said channels being fed by the jets 19a, 19b . . .

When the motor slows down, the depression becomes less without effort, the slide member 10 redescends by its own weight which must be fairly heavy and its fall is braked in the opposite direction by the elasticity of the air contained in the small space 16

beneath the slide member. This latter only reassumes its point of departure when all the air introduced under the pressure of the atmosphere, has been driven out through the hole 17 by the pressure due to the weight of the slide member.

All the pneumatic action, in the physical sense of the word would not be obtained if the distributor slide was not hermetically closed by its end mass 12.

A peripheral groove 20 is provided near the lower part of the slide member 10 and the channel 13 communicates with and has its outlet in this groove. A hole 21 pierced in the lining 8 immediately beneath the locking screw 14 brings the channel constantly in communication with the external air.

The space 16 beneath the slide member 10 may be considered as being constantly held at a pressure in the neighbourhood of the atmospheric pressure owing to the air entering the compensator hole 17 which allows the quantity of air drawn in at the rise of the sliding member to pass with a certain braking action or effort.

On the other hand, the groove or grooves 20 is, or are, always fed largely through the hole 21 with air at atmospheric pressure.

There is thus no chance of leakages toward the bottom of this groove (or grooves) 20 which isolates in absolute manner, the under part of the slide member, from the bottom of the feed apertures 18a, 18b . . . , provided on the periphery.

There is thus no change of leakages. The inside of the slide member 10 and the bottom of the openings 18a, 18b . . . is well subjected to a depression which creates an intake of air from the lower parts at atmospheric depression, but this intake is fed solely by the air situated in 20 instead of being fed by the air 16 drawn through the compensator hole 17.

The slide member 10 is thus balanced at the different speeds, that is to say that equilibrium is established for any determined regime, at a stable balanced position without objectionable oscillatory movement.

On the other hand it is possible to leave, when machining, the slide member, a little clearance sufficient for allowing the sliding without jamming and without detriment to the functioning of the carburetor.

For the same reason, the function of the carburetor is no longer affected by wear thereof and the slide member rises and falls always in the same period or evolution.

In view of the small section of the peripheral groove 20 serving to stop leakage, and of the longitudinal channel 13, the amount of leakage is absolutely negligible in relation to the total volume delivered by the carburetor and in no way affects its operation. Moreover, this quantity of air arising from the leakages only exists at high speeds and slow

running is not at all affected, the slide member being at the bottom of its travel.

For the purpose of obviating, as far as possible, condensation of fuel which might 5 find its way beneath the slide member, by the play allowed in the matching between the latter and the carburetor, it is necessary to avoid movement eddies due to meeting of the fluid streams leaving the radiating channels 10 11a, 11b, . . . serving for the suction.

For that purpose, there is added to the interior and bottom of the slide member a part 22 forming a screen of a shape which has been specially designed to modify the direction of 15 the gaseous streams delivered by the radiating channels 11a, 11b, . . . , so as to direct them in the axis itself of the body of the carburetor and avoid the formation of eddies which would inevitably be produced at the 20 point where the streams of fluid meet.

Another advantage is that the arrangement of the jets for normal running is greatly facilitated. According to the order of delivery of the jets 19a, 19b, . . . the jet 19b 25 opposite the jet 19a only commences to deliver when conduit 11a is uncovered, the same taking place in respect of the jet 19d which is opposite the jet 19c.

There is produced at the moment where the 30 conduits 11b and 11d are uncovered, a counter pressure on the corresponding jets 19b, 19d which retards the correcting action of their entry into play.

By reason of the member 22 forming a 35 screen between the fluid streams 11b and 11a on the one hand and 11d and 11c on the other hand, this counter pressure has no further effect and the operation takes place normally.

Further, at the full speed of the motor, 40 when the distributor 10 is at its top position, the four orifices 18a, 18b . . . deliver in a converging manner all around the member 22 which forms the screen and, as all eddies are avoided, the outflow of the gases is facilitated.

45 At the same time, the better supply to the engine cylinders which results, provides a notable gain of full power.

The member 22 may be integral with the bottom of the slide member or secured there- 50 to by screw 23 or equivalent means; it has, preferably, in plan view the section of the St. Andrew cross (Fig. 2) so as to completely partition the internal space of the slide member and bring the different gaseous 55 streams separately through arcuate conduits 24a, 24b . . . to above the slide member 10, the mixture of the streams of the fluid only taking place in the body 1 of the carburetor.

The arcuate channels 24a, 24b, provided in 60 the member 22, direct the fluid and streams without sudden bends or sudden variations in section.

The advantage of this construction is to 65 maintain the gaseous current always at sufficient speed of travel throughout the carburetor no matter what may be the speed of the motor, which ensures the homogeneity of the mixture by suppressing condensations through loss of speed or loss of charge.

The bearing surface of the slide member 10 70 on the lower plug 15 must be reduced as much as possible so as to avoid sticking through the effect of suction; for this reason or purpose, the slide member rests on feet 24 of reduced surface.

In abnormal operation, the slide member 10 can abut in one or other direction at the end of its travel against the plug 15 on the one hand and against the upper bore of the body 1 on the other hand; the burring of its edges might cause it to jamb in one or other of its extreme positions. For this purpose a disengager has been provided on the upper edge 25 of the slide member 10 and the lower angles 26 of the feet 24 have been chamfered. 75 80 85

The invention is not to be limited to the constructional form which has been described but covers any modifications in details to meet a particular case. In particular, it is obvious that the number, position, depth, width, 90 the shape itself of the peripheral groove or grooves for the stabilization of the leakages as also the longitudinal slot, can vary according to the dimensions of the slide member, without exceeding the scope of the invention. 95

What I claim is:

1. In a multiple jet carburetor, a slide valve arranged to rise by the suction of the motor, an air inlet aperture below the said valve to permit each rising in a regular movement, said valve having a channel leading to the outer air and also having a peripheral groove with which said channel communicates to keep constant the leakages along said valve, 100 to dispense with effects of wear and to permit of machining said member with sufficient play. 105

2. In a multiple jet carburetor, a slide valve having a groove on its periphery near its lower part and a channel to communicate with said groove and with the atmosphere through a hole in the body of the carburetor, and means to guide said valve. 110

3. In a multiple jet carburetor, a slide valve having a peripheral groove and a channel to establish communication of said groove with the outer air, to keep constant the leakages due to wear, said valve having openings and channels admitting air into the carburetor and means to guide and turn the fluid streams and to form a screen between the channels. 115 120

4. In a multiple jet carburetor, a body, a slide valve therein, a screen within the said valve to guide separately the air jets and to ensure their mixture above the slide only, said body having an inner wall spaced from the outer wall and forming an independent lining which serves as a guide for the valve, which by reason of its being spaced from the 125 130

outer wall is not liable to deformation and hence also serves to prevent deformation of the valve, a reduced bearing surface for the slide, to prevent its sticking by suction, and a calibrated opening in the bottom of the body of the carburetor.

In witness whereof I affix my signature.
GEORGES BARIQUAND.
